Primary Examiner — Cynthia R Underwood

(74) Attorney, Agent, or Firm — Charles F. Reidelbach, Jr.

(57) **CLAIM**

We claim the ornamental design for a cover for an electronic device, as shown and described.

DESCRIPTION

FIG. 1 is an upper right front perspective view of a cover for an electronic device;

FIG. 2 is a lower left rear perspective view of a cover for an electronic device;

FIG. 3 is a front elevational view of a cover for an electronic device;

FIG. 4 is a right side elevational view of a cover for an electronic device;

FIG. 5 is a rear elevational view of a cover for an electronic device;

FIG. 6 is a left side elevational view of a cover for an electronic device;

FIG. 7 is a top plan view of a cover for an electronic device; and,

FIG. 8 is a bottom plan view of a cover for an electronic device.

Dashed lines represent unclaimed environment and form no part of the claimed design.
